CLAIM

The ornamental design for an archery bow vibration dampener, as shown and described.

DESCRIPTION

FIG. 1 is a perspective view of an archery bow vibration dampener showing our new design;

FIG. 2 is a front elevational view thereof, the rear being the same in appearance;

FIG. 3 is a right side elevational view thereof;

FIG. 4 is a left side elevational view thereof;

FIG. 5 is a bottom plan view thereof; and,

FIG. 6 is a top plan view thereof.
